UNITED STATES PATENT OFFICE.

RICHARD WILLIAM BAILEY, OF ALTRINCHAM, ENGLAND, ASSIGNOR TO WESTINGHOUSE ELECTRIC & MANUFACTURING COMPANY, A CORPORATION OF PENNSYLVANIA.

TREATMENT OF STEAM TO REDUCE OR PREVENT CORROSION.

Application filed December 17, 1921, Serial No. 523,055, and in Great Britain December 20, 1920.

This invention relates to means for treating steam to reduce or prevent corrosion of apparatus or plants in which it is utilized and while it is applicable generally to steam 5 plants of various kinds, it is directed principally to the reduction or prevention of corrosion of the blading in steam turbines. With this object in view it has already been suggested to provide in connection with 10 steam turbines and other engines a corrodible strainer through which steam is caused to pass before entering the turbine or other engine, the steam in passing through the strainer coming into contact with metals 15 which so far as corrosion is concerned are similar to or not less acted upon than those of the turbine or engine parts in which the steam is to be afterwards employed. It does not, however, appear to have been appreciated 20 that corrosion of the metals in question only proceeds in the presence of moisture and the passing of dry steam through such a strainer as has been heretofore suggested would not necessarily attain the result 25 desired.

According to the present invention a device such as the corrodible strainer heretofore suggested is arranged to be located in the path of the steam from the boiler to the 30 turbine or other appliance at a point where the steam contains a sufficient amount of moisture to enable the device to be effective. Consequently, when the steam is superheated before being used, the device or strainer will, 35 according to the present invention, be located between the boiler and the superheater. Where the steam at no part of its path is in a sufficiently wet or saturated condition to obtain the most effective neutralization 40 or removal of the active corrosive elements contained in the steam, water may be injected into the corrodible strainer in the form of a fine spray or may be caused to trickle over the surface of the material provided in said device or the steam may be 45 partly condensed by passing it through a device somewhat similar for example to a feed water heater of the surface type so that its moisture content is raised to the necessary 50 amount. Preferably, a steam drier or separator is incorporated for the purpose of removing excess moisture from the steam after

it has been treated before its admission to the turbine or other apparatus in which it is to be used.

To enable the invention to be clearly understood it will now be described with reference to the accompanying drawings in which Fig. 1 is a diagrammatic sectional elevation of steam treating apparatus in accordance with the invention, applied by way of example to a water tube steam boiler; Fig. 2 is a sectional elevation of one form of the steam treating apparatus showing the parts thereof in greater detail and Fig. 3 is a section on the line III—III of Fig. 2; Fig. 4 is a sectional elevation of another form of the steam treating apparatus and Fig. 5 is a section on the line V—V of Fig. 4. Fig. 6 is a sectional elevation of a further form 65 of the steam treating apparatus in accordance with the invention. Fig. 7 is a sectional elevation of a still further form of the steam heating apparatus, and Fig. 8 is a section on the line VIII—VIII of Fig. 7. 75

Referring to Fig. 1 of the drawings, 1 is the upper drum forming part of a common form of water-tube boiler, 2 and 3 indicate respectively the front and back water tubes connecting the said drum to a lower drum 80 not shown, and 4 indicates a superheater which is connected to an off-take header 5 and an intake header 6. The latter is connected with a pipe 7 which in the ordinary way terminates in a portion 8 shown in dotted lines within the upper portion of the shell of the boiler above the water level 85 therein. The steam treating apparatus in accordance with the present invention is indicated at 10 and comprises a drum or casing 11 of cylindrical, rectangular or other shape having its ends closed, for example, by caps 12 and 13. The treatment material indicated at 14 consisting of iron plates, expanded sheet, turnings or the like for example, is arranged substantially in the central portion of the casing 11. The casing 11 is conveniently supported on the top of the upper drum 1 of the boiler and is connected with the latter through a pipe 15 through 90 which the steam passes from the drum 1 into the casing 11 thence passing upwards through the treatment material 14 and leaves the said casing by means of an outlet pipe 16

which is connected directly to the pipe 7, the portion 8 being dispensed with. In the case, however, of a new boiler having the treater apparatus in accordance with the invention used therewith, the pipe 16 may be connected to the inlet header 6 of the superheater 4 in any convenient manner.

Steam in a comparatively wet condition enters the treater 10 through the pipe 15 and coming into contact with the treatment material 14 corrodes the latter and its corrosive constituents are thereby reduced. In case the steam does not possess sufficient moisture content for proper corrosive action with the treatment material 14, the incoming steam may be artificially wetted by means of a spray device 17 arranged immediately above the treatment material 14 and supplied with water through a pipe 18 from any convenient source. Water from the spraying device 17 will trickle over the surface of the treatment material 14 and drip into the bottom of the casing 11. A pipe connection 19 with a submerged discharge is provided between the lower part of the casing 11 and the drum 1 of the boiler by which water collecting in the bottom of the casing is passed into the boiler. Said pipe has an inlet 20, which is at a lower level than the inlet of the pipe 15 into the casing 11, but some distance from the bottom thereof, so that the latter can serve as a receptacle for any deposit or débris which may fall from the treater. Within the upper part of the casing is preferably arranged a separator 21 of any well known type through which the steam passes before leaving by the outlet pipe 16. This separator 21 serves to remove the excess moisture from the steam and may advantageously take the same form as the treater and comprise similar material so that in addition to the steam being dried thereby, further or more complete removal of the corrosive constituents of the steam some of which may have been added to the steam by the water supplied for moistening it, takes place in the drying or separating process.

Referring to the detailed and preferred construction of the treater illustrated in Figs. 2 and 3, the treatment material 14 is in the form of a plurality of rectangular plates arranged parallel with one another in vertical planes and spaced apart to permit the steam and water to pass between them. The said plates are carried in a rectangular frame 22 which is open at the top and bottom. An internal flange 23 is arranged around the wall of the casing 11 and a flange 24 is arranged around the outside of the frame 22 near its upper end which rests upon the flange 23 and makes a substantially steam-tight joint therewith so that steam entering the inlet pipe 15 passes around the frame 22 as shown by the arrows 25 (see

Fig. 3) then passes downwards beneath the lower edges of the walls of the frame and thence upwards as shown by the arrow 26 through the plates of the treatment material 14. The steam drier or separator 21 is preferably of similar construction to the treater 14 and is provided with an open-ended rectangular frame 27 having a flange 28 at its lower edges resting upon an internal flange 29 within the drum or casing 11. The steam passes upwards through the treater 14 and the drier 21 and thence passes as shown by the arrows 30 over the top edge of the frame 27 and leaves the casing 11 by the outlet pipe 16. The action of this form of the treating apparatus is the same as that of the apparatus of Fig. 1. The steam enters by the inlet pipe 15 and is deflected by the vertical sides of the frame 22, its speed being greatly decreased owing to the large cross-sectional area of its path. The velocity of the steam after entering the outlet pipe 16 is increased owing to the reduction of the sectional area of the passages through which it passes. In this manner a relatively low steam speed through the apparatus is obtained and the tendency to disturbance at the entrance of the treatment material is reduced. The method of supporting the frames 22 and 27 upon flanges as described, permits the treatment material to be readily renewed or cleaned. It will be understood that instead of rectangular plates the said frames may carry expanded or perforated plates arranged horizontally or vertically or iron turnings may be used. Furthermore, the plates or the like may be arranged in groups or sections or horizontal layers. Or the plates may be inclined and so arranged that steam is caused to take a zig-zag path through the apparatus.

Referring now to the construction of the apparatus illustrated in Figs. 4 and 5, the casing 11 is here arranged with its axis substantially horizontal and supported on the top of the drum 1 of the boiler in any convenient manner. The treatment material 14 consisting of iron plates, for example, is arranged within a frame 31 which is rectangular in horizontal cross section and as before, is open at the top and bottom. The said frame is cut away, as clearly shown, in a slanting direction towards the ends so as to expose the vertical edges of the plates and is provided with flanges 32 substantially in the centre of the two sides thereof which are parallel with the axis of the casing. The flanges 32 rest upon horizontal webs 33 arranged within the casing 11 as clearly shown in Fig. 5. The casing is provided with a partition which fits around the right hand end of the upper part of the frame 31 to provide a substantially steam-tight joint therewith as shown at 34 in Fig. 4. A similar partition 35 is arranged in the lower part of

the other end of the casing 11 and fits around the lower part of the frame 31 also providing a substantially steam-tight joint therewith. These partitions along with the 5 flanges 32 and 33 cause the steam entering by the inlet pipe 15 and leaving by the outlet pipe 16 to assume the path indicated by the arrows, that is, the steam passes upwards through the space in the left hand end of the 10 casing 11 and thence passes downwards and laterally into the treatment material 14. The steam then leaves the plates of treatment material 14 in a downward and lateral direction and passes upwards through the space 15 at the right hand end of the casing 11 leaving by the pipe 16. The spraying device 17 is provided above the treatment material and the outlet pipe 19 is arranged in the manner described with reference to Fig. 2, a valve 36 20 being provided in said pipe if desired. The end covers 12 and 13 being removable, enable the interior of the casing 11 to be inspected and permit the withdrawal of the frame 31 containing the treatment material. 25 In the arrangement illustrated in Figs. 4 and 5, no drier or separator is shown but a separate drier may be employed if desired. In the apparatus of Fig. 6, however, a steam drier or separator is provided in the following manner. The frame 37 containing the treatment material 14 is somewhat similar to the frame 31, described in connection with Figs. 4 and 5 except that the side walls above the flanges 32 are not cut away, the side walls 35 below the flanges 32 being cut away at 38 and 39 at each end as shown. The drum or casing 11 is provided with two partitions 40 and 41 fitting around the upper portion of the two ends of the casing 37 and with a 40 third partition 42 fitting around the lower part of the casing 39 and located a suitable distance along the said casing from the inlet end. With the above described disposition of the partitions 40, 41 and 42, the steam entering by the inlet pipe 15 is caused to pass upwards and laterally into the treatment material 14 into a space 43 in the upper portion of the drum 11 between the partitions 40 and 41 and thence downwards through 45 the treatment material 21 separated from the treatment material 14 by the lower partition 42 and constituting the steam drier or separator. The steam leaves the plates of the treatment material 21 downwards and laterally and passes in the space into the right hand end of the drum 11 and thence outwards through the pipe 16. It will be understood that by suitably disposing the partitions 40, 41 and 42, the steam may be made 50 to pass downwards through the treater 14 and upwards through the drier or separator or upwards through both of these devices. This arrangement possesses the advantage that any corrosive constituents liberated by 55 the spray are carried over the surface of the

treatment material by the steam and are neutralized later, and since the steam passes upwards through the drier 21, a more complete separation of the water from the steam may be obtained. 70

It will be understood that the outlet pipe 19 instead of being connected to the end covers 13 may be connected with the lower surface of the drum as shown in Figs. 1 and 7. In this way the end covers are left free from 75 any connections and can thus be readily removed.

Referring to the arrangement illustrated in Figs. 7 and 8, the drum or casing 11 is provided with a horizontal web 44 extending completely around its inner walls. A vertical partition 45 extends upwards from the lower part of the drum or casing 11 as far as the said web 44 and divides the lower part of the casing into two compartments 46 and 47, one of which is larger than the other as shown. The larger compartment 46 contains the treater 14 carried in a rectangular frame 48 and provided with a flange 49 which is adapted to rest upon the web 44 and at one end upon the upper end of the partition 45. The smaller compartment 47 contains a drier or separator 21 carried in a rectangular frame 50 provided with flanges 51 resting upon the web 44 and at one end also upon the upper end of the partition 45. The treatment compartment 46 is provided with lateral inlet openings 52 connected with the inlet pipe 15 by means of passages 53. The openings 52 are arranged below the web 44 so that the steam entering the pipe 15 passes beneath the lower edges of the frame 48 and thence upwards through the treatment material 14 in said frame. On leaving the treater the steam passes over the upper edges of the frames 48 and 50 and of the partition 45 and thence downwards through the drier or separator 21 into the space beneath the web 44 in the compartment 47. The steam leaves the latter compartment through lateral openings 54 communicating by passages 55 with the outlet pipe 16. The spraying device 17 is provided over the treater 14 in the manner already described. The water outlet pipe 19 is provided as before to drain the water from the treatment compartment 46 into the boiler or elsewhere and a pipe 56 is provided for draining away any water that may accumulate in the separator compartment 47. 110

It will be understood that various valves such as indicated at 57 and 58 in Fig. 4 may be provided for isolating the treating apparatus and suitable by-passes, not shown, so as to permit the boiler to supply steam direct in the event of the said apparatus being out of order and also to permit it being opened up for inspection or other purposes. 115

In carrying out the invention the material employed in the anti-corrosive device or 120

strainer may be of various kinds and the invention is not limited to a specific material for this purpose. In the case of steam turbines having steel blades, one material which is very suitable for the purpose is sheet iron or expanded sheet steel or a light network of steel or steel turnings offering an extended surface may be employed as already described. Where water is injected into the apparatus for the purpose of increasing the moisture content of the steam, a portion of the boiler feed may be employed at the temperature at which it enters the boiler, the quantity being arranged to be a definite fraction of the total feed.

Having now particularly described and ascertained the nature of my said invention and in what manner the same is to be performed, I declare that what I claim is:

1. In a steam generating plant, the combination of a steam conduit, a corrodible strainer interposed in the steam conduit for separating the corrosive contents from the steam, and means for injecting a spray of water into the corrodible strainer.

2. In a steam generating plant, the combination of a steam conduit, a corrodible strainer interposed in the steam conduit for separating the corrosive contents from the steam, means for injecting a spray of water into the corrodible strainer, and a separator for drying the steam after passing through the corrodible strainer.

3. In a steam generating plant, the combination of a steam conduit, a corrodible strainer comprised of a plurality of elements of corrodible material arranged parallel and in closely spaced relation for separating the corrosive contents from the

steam, means for effecting a flow of steam in one direction through the corrodible strainer, and means for introducing a spray of water into the strainer in such a manner that it trickles over the elements in a direction opposite the steam flow, and a separator for drying the steam after passing through the corrodible strainer.

4. In combination, a conduit for conveying steam, a corrodible strainer interposed in the conduit and comprised of a plurality of plates of corrodible material arranged in parallel and in closely spaced relation, means effecting a flow of steam in one direction between the plates, means for injecting water into the strainer and effecting a flow thereof between the plates in a direction opposite to the steam flow, and a separator for drying the steam after passage through the strainer.

5. In combination, a conduit for conveying steam, a corrodible strainer interposed in the conduit and comprised of a plurality of plates of corrodible material arranged in parallel and in closely spaced relation, means effecting a flow of steam in one direction between the plates, means for injecting water into the strainer and effecting a flow thereof between the plates in a direction opposite to the steam flow, means for draining the water injected into the strainer including means for collecting foreign matter introduced with the water, and a separator for drying the steam after passage through the strainer.

In testimony whereof, I have hereunto subscribed my name this 24th day of November 1921.

RICHARD WILLIAM BAILEY.
